[57] CLAIM

The ornamental design for an electronic copying machine with a computer system or the like, substantially as shown and described.

DESCRIPTION

FIG. 1 is a perspective view of an electronic copying machine with a computer system or the like showing my new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and

FIG. 7 is a bottom plan view thereof.
